UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

CRUSHING-MILL.

1,027,222.

Specification of Letters Patent. Patented May 21, 1912.

Application filed October 31, 1911. Serial No. 657,878.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Crushing-Mills, of which the following is a specification, reference being had therein to the accompanying drawings.

10 This invention relates to that class of ring roll crushing mills, such for example as are shown in U. S. Patents Nos. 906,829 and 995,580, and the present invention relates to certain improvements which will provide a 15 mill of the class referred to which may be made at much less cost than is involved in the building of the mills shown by said patents. In other words, the present invention provides a mill, having a rotating anvil ring 20 with which a crushing roll held yieldingly against the inner surface of said ring cooperates, which is of simple design, so that it may be made at comparatively little cost, and thus the present improved mill is 25 adapted for purposes where a large capacity is not required, where cost is a primary consideration, and where ready access to the crushing members is important.

In the accompanying drawings Figure 1 30 is a side view, partly in vertical section, of a mill embodying the present invention. Fig. 2 is a plan view, and Fig. 3 an end view of the same. Fig. 4 is a detail view to show one of the holding yokes or latches for the 35 swinging end head. Fig. 5 is a detail section to show the balancing spring and cooperating parts.

Referring to the drawings, 12 denotes a 40 suitable base provided with standards 13 in which is journaled a driving shaft 14 which carries at one end a head 15, in the form of a spider, and to which head or spider is attached an anvil ring 16. The shaft 14 is driven in any suitable manner, as by gearing, 45 or by a driving belt running on a pulley 17. The rotating anvil ring and the head or spider by which it is carried are inclosed in a casing 18 suitably mounted on or secured to the base 12, and the interior of said 50 casing affords a suitable chamber in which the crushing operation is effected. The end of the chamber within the casing 18 is closed by a swinging head or door 19 provided with suitable lugs or ears 20 by which it is 55 hinged on a post 21 supported from the base

12. This hinged portion or door may be opened when access to the interior of the crushing chamber is desired, and will, of course, be closed when the mill is running.

Pivotaly mounted on the swinging end 60 head 19 is a lever 22 to which is affixed a shaft 23 on the inner end of which rotates a sleeve 24 to which a crushing roll 25 is secured. This pivotal mounting of the lever 22 on the head 19 is effected by means of 65 pivots or trunnions 26 with which the forked lower end of said lever is provided, and which pivots or trunnions are received in bearing boxes 27 on the said head. The upper end of the lever 22 is drawn inward, 70 to force the crushing roll 25 toward the anvil ring 16, by the stress of a spring or springs 28 encircling a sliding bolt 29 passing loosely through a lug 30 formed on the casing 18, and between which lug and a cap 75 or washer 31 on said bolt 29 the said spring or springs are arranged. The bolt 29 is provided at its outer end with a hole or eye through which passes a pin 32, and which pin pivotally connects a yoke or latch 33 80 with the said bolt. The yoke or latch 33 is adapted to overlap or embrace the upper end of the lever 22 and thus serves as a latch for the said lever. Tapped in the yoke or 85 latch 33 is an adjusting screw 34 which abuts against the upper end of the lever 22 so as to secure the yoke or latch 33 in place, and which adjusting screw may be loosened when the said yoke or latch is to be released.

The stress or initial compression of the 90 spring or springs 28 may be regulated or adjusted by means of a nut 35 on the threaded inner end of the bolt 29, while the final stress or pressure of the said spring or springs on the crushing roll may be regulated or adjusted by the screw 34. When the parts are in working position the yoke or latch 33 will be disposed as denoted by dotted lines in Fig. 1 with the inner end of the screw 34 in engagement with the upper 95 end of the lever 22, as hereinbefore stated, and with the parts thus positioned the stress of the spring or springs 28 may be increased or lessened, by turning said screw in or out and thus, through the sliding bolt 29, such 100 adjustment of the screw compressing said springs more or less. In the drawing two springs 28, encircling the bolt 29, and separated by a washer 39, are shown, this being 105 the preferred construction; as shorter coil 110

- springs are less liable to buckle than a longer coil spring would. It will thus be understood that the yoke or latch 33, with its adjusting screw 34, serves as a means for 5 communicating the stress of the spring or springs 28 to the lever 22, and also serves, when engaged with said lever, as a latch for holding the swinging end head or door 19 closed when the mill is running. As an additional means for thus holding the swinging head or door closed said head or door is provided at its side opposite its hinge point with a lug 36 which is arranged to be engaged by a swinging yoke or latch 37 pivoted 10 on the casing part 18 and also provided with an adjusting screw 38, which may be tightened against the said lug 36 to assist the swinging yoke or latch 33 in holding the end head or door 19 tightly closed.
- 15 20 The material to be crushed is fed from a hopper 40 mounted on the casing part 18 to the anvil ring 16 through the medium of a feed spout 41 which is carried by the swinging end head or door 19, so that when 25 the said end head or door 19 is to be opened it will be swung outward beneath the said hopper carrying the feed spout with it. The discharge from the hopper will, in practice, be regulated, as is usual in this class of 30 mills, by a suitable slide or gate not herein shown, as it forms no part of the present invention.
- In order to prevent the crushing roll 25 from dragging on the anvil ring when the 35 end head or door is opened or swung outward, or at other times, a balancing spring 43 is interposed between the end head or door 19 and the lever 22 from which the said crushing roll is supported. This spring 40 43, as herein shown, is housed in a recess in the said end head or door and encircles a bolt 44 the head of which is pressed outward against the lever 22, by the stress of said. 45 spring. The outward movement of the bolt 44 is limited, so as to be just sufficient to lift the roll 25 clear of the anvil ring, by the adjustable nut 45 on said bolt, and the inward movement of said bolt is limited by the closing together of the coils of the said 50 spring, and is ample to prevent any interference (see Fig. 5). The endwise thrust of the shaft 14 is taken by a thrust bearing housed in a casing 46, and an adjusting screw 47 co-operates with the said thrust bearing in such a manner as to permit longitudinal adjustment of the said shaft for the purpose of bringing the anvil ring 16 carried thereby into any desired relation with the co-operating crushing roll 25.
- 55 60 The present improved crushing mill is similar in its operation, to the crushing mills of the patents hereinbefore referred to. The material to be crushed passes from the hopper 40 through the feed spout 41 to the 65 anvil ring against the inner face of which

if is held by centrifugal action as the said ring rotates, and is reduced by the co-operative action of the crushing roll 25 and the anvil ring. When it is desired to obtain access to the chamber of the mill, for any purpose, the screws 34 and 38 are loosened, and the latches or yokes 33 and 37 may then be disengaged respectively from the lever 22 and the holding lug 36 on the swinging end head or door 19, and the latter will then be free to be swung aside on the hinge bolt 21, thereby opening the chamber of the mill.

70 From the foregoing it will be apparent that the present improvement provides a 80 ring-roll crushing-mill which is of simple construction, so that it may be manufactured at comparatively little cost, and is thus particularly well adapted for use where a large output is not required, where the 85 cost of the mill is a primary consideration, and where quick and ready access to the crushing parts is more than usually important, for example, where different products are wanted, from time to time, and cleaning 90 out for the changed product is required.

95 By mounting the spring or springs 28, or other elastic means acting on the crushing roll 25, on the fixed casing 18, instead of on the end head, as in the machines of the 100 patents hereinbefore referred to, simplicity of construction is secured, and the said spring or springs are adapted to serve, in addition to their former function, to assist in holding the end head or door closed.

Having thus described my invention I claim and desire to secure by Letters Patent:

1. In a crushing mill, the combination with a fixed casing, of a rotating anvil ring within the said casing, a swinging end head, 105 a lever pivotally mounted on said head, a crushing roll co-operating with said ring and supported from said lever, a spring or springs supported on said casing, and means whereby the stress of the said spring or 110 springs may be communicated to the said lever.

2. In a crushing mill, the combination with a fixed casing, of a rotating anvil ring within the said casing, a swinging end head, 115 a lever pivotally mounted on said head, a crushing roll co-operating with said ring and supported from said lever, a spring or springs supported on said casing, means whereby the stress of the said spring or 120 springs may be communicated to the said lever, said means comprising a bolt supported on said casing, and a yoke or latch pivotally connected with the said bolt and adapted to embrace the free end of said 125 lever so as to transmit the pressure of said spring or springs thereto.

3. In a crushing mill, the combination with a fixed casing, of a rotating anvil ring within the said casing, a swinging end head, 130

a lever pivotally mounted on said head, a crushing roll coöperating with said ring and supported from said lever, a spring or springs supported on said casing, means whereby the stress of the said spring or springs may be communicated to the said lever, said means comprising a bolt supported on said casing, a yoke or latch pivotally connected with the said bolt and adapted to embrace the free end of said lever so as to transmit the pressure of said spring or springs thereto, and a screw mounted on said yoke or latch and arranged to engage said lever.

4. In a crushing mill, the combination with a fixed casing, of an anvil ring rotated within the said casing, a swinging head or door by which the end of said casing may be closed, a crushing roll coöperating with said ring, a spring or springs for forcing said crushing roll yeldingly toward the said anvil ring, swinging yokes or latches for securing the said end head in closed position, one of said yokes or latches serving as a means to transmit the stress of said spring or springs to the said crushing roll.

5. In a crushing mill, the combination with a fixed casing, of an anvil ring rotated within the said casing, a swinging head or door by which the end of said casing may be closed, a crushing roll coöperating with said ring, a lever mounted on said head and from which said crushing roll is supported, a spring or springs, acting through said lever, for forcing said crushing roll yeldingly toward the said anvil ring, swinging yokes or latches for securing the said end head in closed position, one of said yokes or latches serving as a means to transmit the stress of said spring or springs to the said lever and through the latter to said crushing roll.

6. In a crushing mill, the combination with a fixed casing, of a rotating anvil ring within the said casing, a swinging end head, a lever pivotally mounted on said head, a crushing roll coöperating with said ring and supported from said lever, a spring or springs supported on said casing, means

whereby the stress of the said spring or 50 springs may be communicated to the said lever, and a balancing spring interposed between said head and lever and serving to prevent said crushing roll from dragging on said anvil ring.

7. In a ring roll crushing mill, the combination with a suitable casing, of a rotating anvil ring within said casing, a head closing the end of said casing, a lever pivotally mounted on said head, a crushing roll 60 coöperating with said ring and supported from said lever, and elastic means supported on said casing and connected with said lever and acting on said crushing roll to force the latter toward the working face of the said 65 anvil ring.

8. In a ring roll crushing mill, the combination with a suitable casing, of a rotating anvil ring within said casing, a head closing the end of said casing, a lever pivotally mounted on said head, a crushing roll 70 coöperating with said ring and supported from said lever, elastic means supported on said casing and connected with said lever and acting on said crushing roll to force 75 the latter toward the working face of the said anvil ring, and a balancing spring supported by said head and acting on the said lever in opposition to the stress of the said elastic means.

9. In a crushing mill, the combination with a fixed casing, of a rotating anvil ring within the said casing, a swinging end head, a lever pivotally mounted on said head, a crushing roll coöperating with said ring 85 and supported from said lever, a spring or springs supported on said casing, means whereby the stress of the said spring or springs may be communicated to the said lever, and means whereby the stress of the 90 said spring or springs may be varied to increase or diminish the crushing pressure.

In testimony whereof I affix my signature, in presence of two witnesses.

THOMAS JOSEPH STURTEVANT.
